LEONARD W. HUGHES, OF OAKLAND, AND WILLIAM H. VON HACHT, OF SAN FRANCISCO, CALIFORNIA

DEODORIZING APPARATUS

Application filed February 24, 1930. Serial No. 430,746.

This invention relates to apparatus for purifying or deodorizing the air of toilet rooms and has for its principal object a simple apparatus which functions automatically through functioning of the toilet flushing box. Another object is to provide such apparatus which is housed entirely within the ordinary toilet flushing box so that it is entirely hidden from view yet readily accessible by removing the lid from the flushing box. A further object is to provide such an apparatus which may be installed in a moment's time without the use of tools, simply by dropping it in place within the flushing box and placing the cover of the box in place.

Another object is to provide such an accessory which will not interfere with the regular functioning of the flushing box yet will permit free access thereto. Still another object is to provide a closed housing for the deodorizing agent used which will permit ejection of a small quantity of deodorant each time yet keep the remainder sealed against evaporation of its volatile constituents. Other objects appear in the following description and in the accompanying drawing.

In the drawing hereto annexed Fig. 1 is a vertical section of a portion of a common toilet flushing water box with its mechanism omitted and our deodorizing apparatus fitted in place within the box and with the lid of the box closed.

Fig. 2 is a plan view of the installation with the lids of the box and apparatus removed.

In further detail the common toilet flushing water box is shown at 1 and its lid at 2, the usual flushing mechanism is omitted as it forms no part of the present invention, but the high water level in the box is indicated at 3.

Within the water box is an auxiliary box or receptacle 4 provided with a simple removable lid 5. The receptacle 4 is preferably of L shape in plan and is suspended from the edges of the water box by flat sheet metal hooks 6 so that in putting the receptacle in position it is merely dropped into place and the lid 2 replaced over it.

The L shape of the inner receptacle is such

that its longer leg will lie adjacent the wall side of the water box so as to provide space at A for the usual overflow pipe and flush valve operating apparatus of the box not shown, and the short leg terminates to provide plenty of room at B for the usual ball float valve of the toilet flusher. By reason of the L shape the auxiliary box is prevented from getting displaced and interfering with the operation or accessibility of the flushing mechanism yet will hold a considerable quantity of the deodorizing liquid.

The inner receptacle may be of metal, porcelain or glass and it is fitted with a short outlet pipe 7 preferably clamped in place to an opening in the bottom as indicated and projecting with its lower open end into the water of the flushing box so that it is effectually sealed when the water is at high level.

The upper end of the outlet pipe is flattened into elongated funnel form 7' and tiltably mounted above its forward edge is a dipper 8 provided with a small bowl 9 which fits within a sump 10 when the dipper is dropped into the receptacle and which rises into a domed out portion 11 of the lid 5 when the dipper is raised.

This dipper is mounted on a transversely extending shaft 12 just above the forward edge of the funnel pipe and is rotatably supported in a bearing nut 13 clamped to an opening in the side of the receptacle. Attached to or formed integrally with the outer end of shaft 12 is a laterally extending arm 14 which lies in almost the same horizontal plane as the dipper 8.

At the outer end of the arm 14 is a pivoted link 15 pivotally connected with the upper end of a slidably rod 16 carrying at its lower end a small float 17.

Rod 16 is slidably supported in spaced bearings 18, 19 carried on a light metal bracket projecting below the receptacle 4 and conveniently secured thereto by means of a horizontally extending flat arm 21 which embraces outlet pipe 7 and is clamped in place by the nut 22 of the pipe. Rod 16 is provided with a stop collar 23 or its equivalent to limit its vertical sliding motion in both directions.

The apparatus functions as follows:

100

With a quantity of any liquid deodorant 24 within the receptacle 4, upon flushing the toilet the water bowl falls and float 17 lowers the dipper into the deodorant, and as the 5 water rises the float 17 rises to thereby lift the dipper and discharge a small quantity of liquid into the funnel of the outlet pipe for mixing with the inrushing water just over the usual inlet water valve of the box not shown, 10 the water continues to rise until it seals the outlet pipe, but the dipper float can travel no further on account of its stop collar limiting its movement, so that if the water should rise around the sides of the receptacle it could do 15 no harm as the receptacle is held firmly in place by the heavy lid 2 of the water box.

Owing to the fact that the discharge of deodorant into the water of the box takes place during the turbulent inrushing of the 20 same there is a thorough mixing of the deodorant with the water ready for the next flushing operation.

The apparatus as described will be seen to measure out a predetermined quantity of 25 deodorant or other disinfecting solution each time the flush is operated in an entirely automatic manner, thus requiring no attention at all except simple refilling at comparatively long intervals of time. The cut away or 30 small channel 8' formed along the handle of the dipper spills any excess over the side of the dipper so that the amount discharged when the receptacle is full will be substantially no greater than when about empty of deodorant.

We claim:

1. A receptacle for a deodorant arranged for positioning within a toilet flushing water box, a dipper pivotally mounted for discharging a quantity of the deodorant to the water of the box, a float carried by the receptacle and actuated by the water of said box arranged to operate said dipper upon the refilling of the toilet water bowl with 45 water each time the toilet is flushed, said receptacle provided with an independent lid completely covering and positioned under the regular lid of the water box.

2. A receptacle for a deodorant arranged 50 for positioning within a toilet flushing water box, a dipper pivotally mounted for discharging a quantity of the deodorant to the water of the box, a float carried by the receptacle and actuated by the water of said box arranged to operate said dipper each time the toilet is flushed, said receptacle provided with an outlet for the deodorant sealed by high water level of the water box.

3. A receptacle for a deodorant arranged 55 for positioning within a toilet flushing water box, an outlet from the receptacle to the water box comprising a pipe extending through the bottom of the box into the receptacle to a point above the level of the deodorant and extending into the water tank to

a point below the normal level of the water in the box, a dipper pivotally mounted for discharging a quantity of the deodorant into said pipe for ejection into the water of the box, a float carried by the receptacle actuated by the water of said box arranged to operate said dipper each time the toilet is flushed, and lid completely covering the top of said receptacle.

4. A receptacle for a deodorant arranged 75 for positioning within a toilet flushing water box above the high level of the water, and means actuated by the flushing operation arranged and adapted for discharging a quantity of the deodorant to the water of 80 the box, said receptacle provided with an imperforate lid completely closing the top of the receptacle, completely closed sides, and a bottom provided with a single outlet sealed by the high water in the box.
